(57) **CLAIM**

We claim, the ornamental design for a medical tape strip, as shown and described.

DESCRIPTION

FIG. 1 is a perspective view showing one embodiment of the new design for a medical tape strip;

FIG. 2 is a top view thereof, the bottom view being a mirror image thereof;

FIG. 3 is a front view thereof;

FIG. 4 is a rear view thereof;

FIG. 5 is a right side view thereof, the left side view being a mirror image thereof;

FIG. 6 is a perspective view showing a second embodiment of the new design for a medical tape strip;

FIG. 7 is a top view thereof, the bottom view being a mirror image thereof;

FIG. 8 is a front view thereof;

FIG. 9 is a rear view thereof; and,

FIG. 10 is a right side view thereof, the left side view being a mirror image thereof.
